Specification for Design.

Patented Dec. 23, 1919.

Application filed August 18, 1919. Serial No. 318,417. Term of patent 7 years.

To all whom it may concern:

Be it known that I, ALBERT H. TROYKE, a citizen of the United States, residing at Oak Park, in the county of Cook and State of Illinois, have invented a new, original, and ornamental Design for a Drop-Head-Sewing-Machine Cabinet, of which the following is a specification, reference being had to the accompanying drawings, forming part thereof.

Figure 1 is a perspective view taken from

one corner of the cabinet showing my new design and Fig. 2 is a perspective view taken from the corner of the cabinet which is diagonally opposite that from which Fig. 1 is taken.

I claim:

The ornamental design for a drop-head sewing machine cabinet, as shown.

ALBERT H. TROYKE.
